UNITED STATES PATENT OFFICE.

EDWARD M. HEYLMAN, OF SOUTH BEND, INDIANA, ASSIGNOR TO OLIVER CHILLED
PLOW WORKS, OF SOUTH BEND, INDIANA.

MULTIPLE-GANG HARROW.

Application filed November 13, 1919. Serial No. 337,823.

To all whom it may concern:

Be it known that I, EDWARD M. HEYLMAN, a citizen of the United States, and a resident of South Bend, in the county of St. Joseph and State of Indiana, have invented certain new and useful Improvements in Multiple-Gang Harrows; and I do hereby declare the following to be a full, clear, and exact description of the invention, such as will enable others skilled in the art to which it appertains to make and use the same.

This invention relates to improvements in harrows and more particularly to disk harrows of the multiple-gang type in which two-disk-gangs are arranged in tandem relation to two other disk-gangs,—one object of the invention being to so connect together two frames with which the front and rear gangs are respectively connected, that the rear gangs will be permitted to swing clear of the front gangs on making a turn and so that a short turn may be accomplished.

A further object is to provide a structure of the type specified in which the rear gangs may be set at an angle to the front gangs and comparatively close to the latter, and still permit the turning of the harrow without conflict of the front and rear gangs.

A further object is to construct the harrow in such manner that in turning, the outside rear gang will assume a greater angle than that of the inside rear gang and hence tend to force the rear gangs back toward alignment with the front gangs as the harrow completes a turn.

A further object is to so construct a harrow comprising two frames pivotally connected together and each frame having disk gangs connected therewith, that the power necessary to pull the rear gangs operates to force the disks of the front gangs into the ground.

A further object is to construct the harrow in such manner that when operated on a hill-side where the tendency of the harrow is to drift down hill, the gang on the "up-hill" side may be caused to assume a greater angle than the angle assumed by the gang on the "down-hill" side, thus causing the rear gangs to correctly "track" with the front gangs on the hill-side.

A further object is to provide simple and efficient means for angling and for adjusting the angularity of the gangs.

With these and other objects in view, the

invention consists in certain novel features of construction and combinations of parts as hereinafter set forth and pointed out in the claims.

In the accompanying drawings, Figure 1 is a plan view of a harrow showing an embodiment of my invention. Fig. 2 is a side elevation. Fig. 3 is a plan view showing the positions which the parts may assume when the harrow makes a turn. Figs. 4 to 10 inclusive are detail views.

1, 2 represent two frames, a portion of the rear frame overlying a portion of the front frame and pivotally connected with said front frame rearwardly of the forward end and forwardly of the latter and preferably in a plane somewhat above that of said front frame, and with each of said frames, disk gangs are connected, as hereinafter described.

The front frame 1 has a general triangular shape, comprising side beams 3, 3 which converge at their forward ends and their rear spread portions are connected by a transverse brace 4 secured to said side beams through the medium of brackets 5. Centrally located, parallel beams 6, 6 extend from the convergent forward ends of the side beams to the transverse brace 4,—the forward ends of said parallel beams being secured to the forward ends of the side beams by bolts 7 and their rear ends resting on the transverse brace. A bracket 8 is secured to the central portion of the transverse brace and provided with a part 9 entering between the parallel beams 6 and secured thereto.

In addition to connecting the forward ends of the beams 3 and 6, the bolts 7 also serve to connect the lower ends of standards 10 with the forward end of the frame 1 and braces 11 extend forwardly from these standards to the parallel beams 6. The rear ends of the members of a yoke or draw-bar 12 (whereby the harrow may be connected with a tractor) are loosely mounted on the bolts 7 and braces 13 are secured at their upper ends to the standards 10, the lower forward ends of these braces being adjustably connected with the yoke or draw-bar. To effect such adjustable connection of the braces 13 with the yoke or draw-bar the members of the latter may each be provided with a plurality of holes 14, to receive the connecting bolts for said braces.

By connecting the yoke or draw-bar with the frame 1 in the manner above described, it may be adjusted vertically to insure a proper draft connection between the harrow 5 and the tractor.

The rear front 2 is triangular in shape and comprises a rear beam 15 and side beams 16 extending forwardly from the ends of said rear beam and terminating at their

- 10 forward ends over an intermediate portion of the frame 1. A central beam 17 is connected at its rear end with the rear frame beam 15 and passes, at its forward end, between the convergent forward ends of 15 the side beams 16, to which latter, said central beam is secured. The central beam 17 projects forwardly and downwardly from the forward end of the frame beams 16 and forms a tongue 18 which is pivotally connected, by a bolt 19, with the top of a bracket 20 secured to and projecting upwardly from the parallel beams 6 of the front frame 1. Braces 21 extend from an intermediate portion of the center beam 17 25 of the rear frame to the converging side beams 16 of the latter.

Disk gangs 22, 22 are loosely connected with the rear portions of the front frame beams 3, 3, and disk-gangs 23, 23 are pivotally connected with the rear corners of the 30 rear frame 2, and mechanism is provided, as hereinafter explained, for adjusting the angles of the respective gangs of each pair and for adjusting the angles of the gangs 35 of one pair relatively to the angles of the other pair.

Each disk-gang comprises a frame including a top beam 24, an axle 25 on which the disks 26 of the gang are mounted, and 40 two standards 27 and 28. Scrapers 29 for the disks are secured to the top beam of each gang frame.

The standards 27 of the respective gang-frames are made near their lower ends with 45 openings 30 into which the rear ends of the front frame bars 3 enter loosely and pins or keys 31 prevent displacement of the gang frames relatively to said frame bars. A link 32 is loosely connected with the upper portion of the standard 27 of each front gang frame, and the other end of each link is 50 loosely connected with the adjacent frame bar 3, through the medium of the bracket 5 secured thereto. Thus it will be seen that 55 each front gang 22 is loosely and pivotally connected at one side of its center with the rear portion of the front frame 1.

In effecting pivotal connection of the rear gangs 23 with the rear frame 2, a bracket 33 60 is secured upon the top beam 24 of each rear gang-frame near the outer end of said top beam, and each bracket 33 is connected with a rear corner of the frame 2 by a pintle 34. A diagonal supporting brace 35 is attached at one end to each frame beam 16

of the rear frame and at the other end, these braces are loosely connected with the lower portions of the standards 27 of the rear gang-frames approximately in line with the pivotal connections of these gang-frames with the rear frame 2. 70

Slidably mounted upon the rear frame 2 and passing freely through guides 36 thereon, are bars 37 and with the latter, inclined bars 38 are connected between their 75 ends. The lower ends of the inclined bars are loosely connected with the standards 28 near the inner ends of the rear gang-frames and the said inclined bars are connected by links 39 with the upper portions of said rear gang-frame standards 28. Vertical bars 40 are connected at their lower ends with the inclined bars 38 and the upper portions of these vertical standards are movably connected with the slide bar 37 by 80 means of pin-and-slot connections as indicated at 41. Thus it will be observed that the rear gangs are connected with the frame 2, not only through the medium of the pivotal connections with the rear corners of 85 the latter, but also by braces 35 and the bars 37, 38 and 40, said bars being connected with those end portions of the gang-frames farthest removed from the pivotal connections of gang-frames with the rear frame 2. 90 95

Levers 42 are pivotally connected, between their ends, to respective sides of the bracket 20 on the front frame 1, and to the lower arms of these levers, the forward ends of bars or pitmen 43 are pivotally connected, 100 the rear ends of the latter being loosely connected with the standard 28 near the inner ends of the frames of the front gangs 22, and links 43 connect the upper portions of said standards with the bars 43. In 105 order to limit the upward movement of the rods or pitmen 43, stops 44 are adjustably secured to the bracket 8 at the rear ends of the parallel bars 6 of the front frame 1.

Interiorly threaded sleeves 45 are pivotally connected with the upper ends of the inclined bars 38 and through these sleeves, the threaded portions 46 of rods or pitmen 47 pass, the forward ends of the latter being loosely connected with the upper arms 115 of the levers 42.

It is evident that if the levers 42 be turned on their pivotal connections with the bracket 20, motion will be transmitted through the rods or pitmen 43 and 47 to the inner portions of the front and rear gangs and operate to shift said gangs on their pivotal connections with the respective frames 1 and 2,—the direction of turning movement of the rear gangs being reverse to the direction of 120 turning of the front gangs,—and thus the angular relation of the front gangs to each other and the reverse angular relation of the rear gangs to each other may be effected.

For operating the levers 42 to effect the 130

simultaneous angular adjustments of the front and rear gangs, the devices now to be described are employed.

An interiorly threaded sleeve 48 is located 5 between the upper ends of the levers 42 and is provided with trunnions 49 mounted in said levers. A sleeve 50 is located between the upper ends of the standards 10 at the forward end of the frame 1 and provided 10 with trunnions 51 mounted in said standards. A manually operable shaft 52 (preferably having a crank handle 53 at its forward end) passes freely through the sleeve 50 and is prevented from longitudinal movement relatively thereto, by pins 54 and collars 55 may be disposed on the shaft between said pins and the ends of the sleeve 50. The shaft 52 is made with a threaded portion which passes through the interiorly 20 threaded sleeve 48 at the upper end of the levers 42, thus effecting a screw-connection between said levers and shaft. It is evident that by turning the screw shaft 52, the levers 42 will be moved and the angular 25 adjustments of the several disk gangs will be effected as previously explained. The threaded portion of the adjusting screw-shaft 52 is enclosed by tubes 56-57 screwed into respective ends of the sleeve 48. The 30 forward end of the tube 56 is provided with a collar 58 through which the plain portion of the shaft 52 passes and this ring may carry a packing ring 59. The rear end of the tube 57 is closed by a cap 60. The tubes 35 56-57 serve to protect the threaded portion of the screw shaft from dust and also serve to contain lubricant.

The location of the pivotal connection of the rear frame 2 with the front frame is an 40 important feature of my invention and, with the cooperation of other features, results in marked advantages in the operation of the harrow. By pivotally connecting the forward end of the rear frame with the front frame forwardly of the rear end and rearwardly of the hitch means at the forward end thereof, the front and rear gangs are located comparatively close to each other and still the rear gangs are permitted to 45 swing clear of the front gangs when the harrow is making a turn and furthermore, a short turn can be made. In turning, the outside rear gang will be caused by the connections hereinbefore described to take a 50 greater angle than the inside rear gang as indicated in Figure 3 and hence has a tendency to force the rear gangs and rear frame back to alignment with the front gangs, as the harrow completes a turn.

In using the harrow on a hill-side, the natural tendency is for the harrow to drift 55 down the hill, but by reason of the location of the connection of the front of the rear frame relatively to the front frame as previously stated, and the pivotal connections

of the connecting bars by which the angular 70 adjustments of the gangs are effected, relatively to the pivotal connection between the frames, the rear gang on the "up-hill" side will assume a greater angle than the rear gang at the "down-hill" side, and this will cause the rear gangs to track correctly with the front gangs on the hill-side, because the upper rear gang has a tendency to climb 75 the hill and keep the rear gangs in proper alignment.

It will be observed that the pivot of the 80 rear frame to the front frame is above the plane of the hitch to the tractor, and hence the power necessary to pull the rear frame and gangs operates to force the disks of the front gangs into the ground. As the front gangs loosen up the earth, the rear gangs will readily conform in depth of penetration 85 to that of the front gangs.

The front end of the front frame, the point of hitch will not rise, because the weight of the tractor will hold it down.

Various changes might be made in the 90 details of construction of my invention without departing from the spirit thereof or limiting its scope, and hence I do not wish to restrict myself to the precise details herein set forth.

Having fully described my invention what 95 I claim as new and desire to secure by Letters-Patent, is:

1. In a multiple gang harrow, the combination with front and rear frames pivotally connected together in line with the 100 longitudinal axis of the front frame, and two earth working gangs pivotally connected with each frame, of upright angling levers pivoted between their ends to the front frame forwardly of the pivot point connecting the frames and disposed at respective sides of the longitudinal axis of the front frame, connections between the lower arms of said levers and the forward earth working gangs; connections between the upper arms of said levers and the rear earth working gangs, said connections having both vertical and transverse pivotal connections with said angling levers, and means operable normally to hold said levers against 105 movement.

2. The combination with front and rear frames, the rear frame overlying the front frame and pivotally connected with the latter rearwardly of the forward end of the same, of two disk gang frames pivotally connected with the front frame, two disk gang-frames pivotally connected with the rear frame, levers pivotally mounted between their ends on the front frame, and connections between said levers, respectively above and between their fulcrums and the disk gang frames at the ends of the rear and front frames respectively. 115 120 125 130

3. The combination of two frames disposed in tandem relation to each other, the rear frame being connected with the front frame between the ends of the latter, earth working gangs pivotally connected with the respective frames, standards secured to the forward end of the front frame, a yoke constituting a draw-bar pivotally connected with said front frame, and braces connecting said standards and draw-bar, the connection of the braces to one of said parts being adjustable.
4. In a multiple-gang harrow, the combination with front and rear frames, and earth working gangs pivotally connected with each frame, of standards located near the forward end of the front frame, levers pivotally connected between their ends with an intermediate part of the front frame, connections between the lower arms of said levers and the front gangs, connections between the upper arms of said levers and the rear gangs, a sleeve pivoted between said standards, an interiorly threaded sleeve pivoted between the upper arms of said levers, and a manually operable shaft mounted in said first mentioned sleeve and having a threaded portion passing through the threaded sleeve pivoted to said levers.
5. In a multiple-gang harrow, the combination with framework, and two pairs of pivoted earth working gangs, one pair disposed in front of the other, of a lever pivoted between its ends, connections between the lower arms of said lever and the front gangs, connections between the upper arm of said lever and the rear gangs, a manually operable screw shaft, a mounting for the latter, and a threaded connection between said screw shaft and the upper arm of said lever.
6. In a multiple-gang harrow, the combination with front and rear frames connected together, and earth working gangs pivotally connected with the respective frames, of levers pivotally connected between their ends with the front frame, connections between the lower arms of said levers and the front gangs, slide bars mounted on the rear frame, connecting bars between slide bars and the rear gangs, and rods connected with the upper arms of said levers and having threaded connection with said connecting bars.
7. In a multiple-gang harrow, the combination with front and rear frames connected together, and earth working gangs pivotally connected with the respective frames, levers pivotally connected between their ends with the front frame, connections between the lower arms of said levers and the front gangs, slide bars mounted on the rear frame, inclined bars connecting said slide bars with the rear gangs, vertical bars connected with said inclined bars and movably connected with the slide bars, and rods adjustably connected with said inclined bars and connected with said levers.
8. In a multiple-gang harrow, the combination with front and rear frames, of earth working gangs pivotally connected with the front frame, earth-working gangs each pivotally connected near one end with the rear frame, braces connecting the pivoted ends of said rear gangs with the rear frame, slide bars mounted on said rear frames, inclined bars connecting said slide bars with the rear gangs, links connecting said inclined bars with the rear gangs, vertical bars connected near their lower ends with the inclined bars and movably connected near their upper ends with said slide bars, levers pivotally connected between their ends with the front frame, connections between the upper arms of said levers and said inclined bars, and connections between the lower arms of said levers and the front gangs.
9. In a multiple-gang harrow, the combination with connected front and rear frames, and front and rear earth-working gangs pivotally connected with the respective frames, of standards on the front frame, levers pivotally connected between their ends with the front frame, connections between said levers, respectively above and below their fulcrums, and the rear and front earth-working gangs respectively, an interiorly threaded sleeve pivoted to said levers, a manually operable shaft, a mounting for said shaft carried by said standards, said shaft having a thread portion passing through said interiorly threaded sleeve, and tubes secured to said last-mentioned sleeve and enclosing the threaded portion of said shaft.

In testimony whereof, I have signed this specification in the presence of two subscribing witnesses.

EDWARD M. HEYLMAN.
